UNITED STATES PATENT OFFICE.

ETTORE F. GIANNATTASIO, OF NEW YORK, N. Y.

DRIVING MECHANISM.

Application filed January 9, 1924. Serial No. 685,194.

My invention relates to improvements in driving mechanisms applied to a prime mover with the object in view of conserving the power supplied to said prime mover. Under ordinary working conditions, the motor or prime mover, or the like source of power, will transmit its energy through a fly wheel or other device which after being started will move by inertia, so that if the power supply to the prime mover is interrupted, the inertia means will carry forward the driving mechanism without appreciably slowing down. My invention is adapted to utilize this principle by frequent interruptions of the power supply to the prime mover, these periods being brief, and permitting the inertia means to be utilized during the interval of interruption without interfering with the operation of the prime mover. A fly wheel may be used as one of the means of utilizing inertia, or a revolvable body flexibly connected to said prime mover, although this means is not imperative, as it is possible to use the inertia of the motor or rotor for this purpose, and the apparatus illustrated in the drawing is only by way of example, and illustrates one way of carrying out my invention.

My invention is intended to provide an effective means for automatically interrupting the power supply for the prime mover, and permitting the parts already set in motion to move by inertia until the power supply is turned on again.

Reference is to be had to the accompanying drawings forming a part of this specification, in which similar reference characters indicate corresponding parts in all the views.

Figure 1 is a plan view partly in section of an embodiment of my invention.

Figure 2 is a side elevation thereof.

Figure 3 is a detail of a brake mechanism which can be used to control the speed of the apparatus,

Figure 4 shows details of ratchet wheels forming a part of the connection, and

Fig. 5 is a diagrammatic view of the electric circuit associated with the invention.

In the drawings the prime mover 46 is an electric motor which is mounted on a suitable base 10, having posts 11, and is connected through a chain of gearing to the inertia means 12. In the examples shown this inertia means has a drum 13 loosely

mounted on a shaft 14 which is journaled in supports 15 on brackets 16. Within the drum 13 is a coil spring 17, one end of which is secured by a set screw 18 to a hub within the drum 13, and this hub is made fast to the shaft 14 by a set screw 20. At its outer end the spring 17 is attached to the drum 13 by a set screw 21^a. The drum 13 has an extension 21 connected to the pulley 22 from which power may be taken. The member 21 serves the purpose of a brake drum, and is frictionally engaged by a brake band 23, one end of which is secured at 24 to a support, and the free end is secured to a yoke 25 attached to the core 26 of the solenoid 27, and this solenoid is in the electric circuit *a-a'* in which is a switch 28 by which the circuit can be opened and closed. The pulley 22 is provided with a belt 29 to transmit power, though power may be taken from the shaft 14 in any suitable way.

The shaft 14 is driven by a sprocket wheel 30, chain 31, and sprocket wheel 32 on the shaft 33 which is mounted in bearings 34, 35 and 43. Secured to the shaft by a key 36^a is a collar 36 which is provided with ratchet teeth 37 which engage ratchet teeth 38 on the second collar 39. The collar 39 is provided with a shank 39' which is slidable within a stationary sleeve 41 connected to the bracket 43, and the collar is normally urged forwardly, or towards the collar 36 by a spring 100 which latter encircles the shaft 33 and bears against the bracket 43, all of which is clearly shown in Figure 1. The motor 46 is connected by supply wires *b-b'* with the binding posts 47 and 47' respectively of the switch or circuit breaker B, and this has a tilting contact plate 48 having a cross bar 48' which latter carries contacts 49' so positioned as to make contact with the contacts 49 connected to wires *b²* and *b³* leading to binding posts 50. The binding posts 50 are connected by leads 50' with binding posts 50^a which latter are connected to the solenoid 27 by leads *a-a'*. The lead *a* has a switch 28 therein for breaking the circuit through the solenoid 27. As shown clearly in Figure 5 the binding posts 47 and 47' are connected to the binding posts or contacts 49 by wires 52' and 53' respectively. 59 and 60 designate leads from a source of supply which leads are connected to the binding posts 50^a.

On top of the tilting plate 48 which is normally held open by a spring 53, is a striking arm 52 which is arranged near the cam wheel 54, this turning on a shaft 55 and having rollers 56 to strike the arm 52 at intervals, and thus close the plate 48 against the contacts 49, thereby closing the switch B for a short interval. The shaft 55 connects with the shaft 14 by gears 57 and 58, therefore when the motor 46 is started, the motion is transmitted through the flexible inertia means above described to the cam 54, and the roller abutments strike the arm 52 and close the circuit to the motor through the switch 48.

It will be seen that the current will flow in through the circuit $a-a'$, b^2-b^3 , the switch B, and the circuit $b-b'$ to the motor, and that the circuit will be interrupted by the switch B as described, and during this interval the rotation of the shaft 14 will be kept up by the inertia unit 12 attached thereto. The speed of the unit may be controlled by the switch 28 which when closed will apply the brake strap 23 by reason of the action of the magnet 27.

It will be clear, therefore, that the mechanism between the prime mover, as for instance the motor 46, and a driven member, as for instance the pulley 22, can be any suitable driving connection, and it will likewise be understood that when I refer to cutting out the power supply to the motor, I mean to include any such reduction of the power supply as will cause the inertia element included in the mechanism whatever it may be, to act by momentum under the impulse imparted to it by the motor so as to maintain the speed of the driven member during the period of cutting out or reduction without appreciable loss.

From the above description, it is believed the invention will be fully apparent to those skilled in the art and I desire it understood that various changes may be made in the form and proportions of the device, such as fall within the scope of the appended claims without departing from the spirit of the invention.

50 I claim:

1. In apparatus of the kind described, means for conserving power comprising in combination, a motor, a transmitting element driven by the motor and biased to turn by its own inertia when in motion, and means for intermittently and periodically cutting off the power supply to the motor at regular intervals.

2. In apparatus of the kind described, means for conserving power comprising in combination, a motor, power transmitting means connected with the motor, a member connected to the motor and adapted to turn by inertia when set in motion, and means for intermittently and periodically cutting

off the power supply to the motor at regular intervals.

3. A constantly running motor, a power transmitting means driven by the motor and operating by inertia when the power supply of the motor is cut off, and means operative to cut off the power supply to the motor whereby power is delivered to the power transmitting means by periodic impulses at regular intervals. 75

4. In an apparatus of the kind described, means for conserving power comprising in combination with a motor and power transmitting means driven by said motor, an inertia unit forming a part of the power transmitting means, and means for cutting off the power supply to the motor at regular periodic intervals, said inertia unit operating by inertia during the periods that the power supply is cut off whereby to transmit power during such periods. 85

5. In apparatus of the kind described, means for conserving power comprising in combination, a prime mover adapted to move by inertia when its power supply is cut off, and means for intermittently and periodically cutting the motor power supply to said prime mover in and out at regular intervals. 90

6. In an apparatus of the kind described, means for conserving power comprising a prime mover, a driven member, and a member forming an element of the connection between the prime mover and the driven member and movable by momentum when the power supply of the prime mover is cut off, and means for cutting off said power supply at regular intervals. 95

7. In an apparatus of the kind described, a motor, power transmitting means operated by said motor and including an inertia element, and means for intermittently and periodically cutting off the power supply to the motor at regular intervals and permitting such inertia element to operate said power transmitting means during the periods of interruption of said motor power supply, said power interrupting means being so arranged that the periods of interruption of said motor power supply are independent of the speed of the motor. 110

8. An apparatus of the kind described, comprising a motor, a power transmitting element operated by said motor and including an inertia element, means operated by said power transmitting element for intermittently and periodically cutting out the power supply to the motor at regular intervals, said inertia element operating by its own momentum during the periods of interruption of the motor power supply to transmit power. 120

9. An apparatus of the kind described comprising a motor, a power transmitting element operated by said motor and includ- 130

ing an inertia element, means operated by said power transmitting element regardless of the speed of said motor for intermittently and periodically cutting off the power supply to the motor, at regular intervals, said inertia element operated by its own momentum during the periods of interrup-

tion of the motor power supply to transmit power.

In testimony whereof, I have signed my name to this specification this 5th day of January, 1924.

ETTORE F. GIANNATTASIO.
